UNITED STATES PATENT OFFICE.

WILLIAM BRUCE THOMPSON, OF THORNBANK, DUNDEE, SCOTLAND.

BOILER-RIVETING MACHINE.

1,296,139.

Specification of Letters Patent.

Patented Mar. 4, 1919.

Application filed January 30, 1918. Serial No. 214,444.

To all whom it may concern:

Be it known that I, WILLIAM BRUCE THOMPSON, a citizen of Great Britain, residing at Thornbank, Dundee, in the county of Forfar, Scotland, have invented new and useful Improvements in Boiler-Riveting Machines, of which the following is a specification.

This invention relates to a hydraulic machine for riveting boilers and has for its object to provide a machine for riveting parts of boilers which are usually riveted by hand. For instance, single ended marine front plates are usually riveted by hand, because there is not sufficient room between the front ends of the furnaces and the front plate to allow of this plate being riveted by power.

With the present invention such inaccessible parts can be riveted by power very successfully.

The following description and accompanying drawings show a manner of carrying out the invention.

Referring to the drawings:

Figure 1 is a side elevation of a machine.

Fig. 2 is a plan of Fig. 1.

Fig. 3 is an end elevation of Fig. 1.

Fig. 4 is an enlarged vertical section on the center line of the riveting head.

The riveting head 1 is secured to a bed 2, to the other end of which bed is bolted a holder up device 3. A portion of a suspended boiler *a* in the process of having a rivet *b* put in, is shown in dot dash lines in Fig. 1, a portion of the holder up device protruding through the hole *c* of the boiler.

The riveting head consists of a hollow cylinder 4 within which is located the main ram 5 provided with a chuck 6 which carries the steel tup 9, having a partly spherical recess 10 for forming the head of the rivet. The ram is provided with a packing ring 8 which secures in place a leather 11 for the purpose of making a joint between the ram and the cylinder. An inlet and outlet vent 12 is provided which can admit water to, and release it from, the rear of the ram 5.

Secured to the rear of the main ram is a second ram 13 which extends through a bore in the rear of the cylinder 4 into a chamber 14 located at, and secured to the rear end of the cylinder 4. The chamber is of greater diameter than that of the bore. This second

ram is provided with a piston head 15 carrying a cup brass 16, for the purpose of making a joint between the ram and the walls of the chamber, the piston being secured to the ram by a nut 17. A brass liner comprising sections 18 and 22 is inserted between the bore and the ram 13, such sections being spaced apart and having their inner ends provided with leather cups 19 and 21 respectively, between which is interposed a distance piece 20 for securing the cups in place to prevent water leaking from the cylinder 4 to the chamber 14, or vice versa. The sections of the liner are prevented from endwise movement by the end of one abutting against the head 23 of the ram 13 and the end of the other abutting against the piston head. A vent 24 permits access of water to the chamber 14, this vent being always open and the water always under pressure.

The base 2 is built up of H section girders and is provided with slotted holes 25 to allow the holder up device to be secured nearer or farther away from the riveting head as desired, according to the distance the hole *c* is from the point to be riveted.

The holder up device consists of a base 26 secured by bolts 27 to the main base 2. A perpendicular pillar 28 has keyed to it, by a key 29 a holder up arm. This arm is divided longitudinally of its length, so that each part may be put through the hole *c* separately and afterward united by bolts 30. The arm is composed of sections, 31, 32, 33 and 34 respectively, each section being connected by bolts to the next. The end section 34 carries a tup 35 which presses against the head of the rivet. The pillar 28 is bored out at 36 for the purpose of admitting an air compressor tube to the interior of the boiler, to operate a calking or other pneumatic tool when it is required for work inside the boiler, an inlet 37 being provided so that the tube may pass into the bore 36. Passing the compressor tube through the center of the pillar 28, permits the pneumatic tool to be used when the boiler is turned around without winding up the tube, as would be the case if the tube entered through the manhole at the side.

In operation, the boiler *a* is lowered so that the pillar 28 passes through the hole *c*; it can thus be turned about the pillar as required for riveting. The two halves of the holder up arm are then secured in posi-

tion on the pillar 28, the key 29 securing the arm to the pillar, the sections 32 and 33 having been previously put in or taken out according to the distance the seam to be riveted is from the hole *c* and the holder up device secured in the proper position on the bed 2. When everything is ready for the riveting to begin water is admitted at the vent 12 to the rear of the ram 5, which ram 10 is thereby forced forward, the tup 9 effecting the necessary work on the rivet *b*. Water under pressure is also admitted at the vent 24, but this vent is always open and the water under pressure is always working 15 against the piston 15 and therefore continually tending to draw back the ram 5. Owing, however, to the area of the head of the ram being greater than the area of the piston, the ram is forced forward when the 20 vent 12 is opened. When, however, the pressure on the ram is released the pressure on the piston asserts itself and the ram is drawn backward, the water behind the ram being forced back through the vent 12 to 25 the accumulator.

I claim:-

1. A boiler riveting machine comprising a riveting head, a holder up device, a pillar forming part of said device, a holder up arm 30 divided longitudinally and mounted on said pillar, and a base carrying said riveting head and said holder up device.

2. A boiler riveting machine comprising a riveting head, a pillar forming part of said

device, a holder up arm mounted on said 35 pillar and divided longitudinally and built up of independent sections, and a base carrying said riveting head and said holder up device.

3. A boiler riveting machine comprising a riveting head, a holder up device, a pillar forming part of said device, a holder up arm 40 detachably mounted on said pillar and divided longitudinally and built up of independent sections, a tup on said end section, 45 and a base carrying said riveting head and said holder up device.

4. A boiler riveting machine comprising a riveting head, a holder up device, a pillar forming part of said holder up device, a 50 holder up arm detachably mounted on said pillar divided longitudinally and built up of independent sections and mounted on said pillar, a hollow bore in said pillar, a base carrying said riveting head and said holder 55 up device, and slotted holes in said base for the purpose of adjusting the holder up device to the length of the holder up arm when sections are taken out of said arm or inserted.

In testimony whereof I have signed my name to this specification in the presence of two subscribing witnesses.

WILLIAM BRUCE THOMPSON.
